UNITED STATES PATENT OFFICE.

AMBROSE KOWASTCH, OF BERLIN-CHARLOTTENBURG, GERMANY.

FUSE FOR BLASTING WITH A LIQUEFIED GAS AND METHOD OF PRODUCING THE SAME

1,424,487.

Specification of Letters Patent. Patented Aug. 1, 1922.

No Drawing.

Application filed July 19, 1920. Serial No. 397,557.

To all whom it may concern:

Be it known that I, AMBROSE KOWASTCH, of Berlin-Charlottenburg, Leibnizstr. 78, in the States of Prussia and German Empire, have invented certain new and useful Fuses for Blasting with a Liquefied Gas and Methods of Producing the Same, (for which I have filed an application in Germany, August 18, 1916), of which the following is a specification.

My invention relates to fuses or ignitors for blasting with a liquefied gas, such as liquid air and to a method of producing the same.

15 In the fuses or ignitors known up to the present time, azoimide of lead, lead azide, or such like substances of high initial power have been used as a headpiece, acting as a plug in place of fulminate of mercury but 20 not in admixture with other substances.

According to the present invention soot powdered cork dust, or similar substances adapted to absorb a liquefied gas are intimately mixed with a ready made explosive of 25 high initial power such as azoimide of lead, fulminate of mercury or trinitrotoluol.

The chief purpose of such a thorough mixture for fuses or ignitors consists in obtaining an equal and uniform density of charge, 30 hitherto not attainable whilst at the same time removing any danger of explosion in handling said fuses or ignitors as long as they are not soaked or saturated with liquefied air. This safety does not exist when 35 azoimide of lead or similar substance is used as a top piece or plug. Further in a fuse made according to the present invention, azoimide of lead or similar substance would still be dangerous in view of the possibility 40 of explosion or spontaneous ignition, were a thorough intermixing or commingling of the said azoimide of lead with components of the fuse, such as carbon carriers or the like, not be effected. After such an intimate mixture, however, said danger is completely 45 removed.

A mixture of for instance 30 percent of azoimide of lead and seventy percent of carboniferous substances or carbon-carriers 50 would, when exposed to a strong heat, and without being saturated with liquid air, burst into flames and be consumed without explosion. However, by the admixture of the explosives mentioned above the density 55 of the charge is increased, and in consequence, the effect produced considerably

enhanced. A much greater density of charge is thus obtainable than in a plain fuse or ignitor with pure liquid air.

Plain fuses or ignitors with liquid air, it is true possess a high explosive power, but if this should not be sufficient in certain cases for any purpose, and if it be desirable or necessary to get the wave of detonation considerably intensified and accelerated, this may be brought about by adding one of the explosives mentioned above. This mixture or blend supplies and furnishes, in spite of the low temperature of the liquid air, an initial blasting substance or explosive, which, as experiments have proved, by far surpasses, the effect of a pure unmixed initial blasting substance like that of plain azoimide of lead or pure fulminate of mercury or the like. This is shown by the fact that, for example explosives which cannot be brought to initial detonation by certain quantities of azoimide of lead or fulminate or mercury or such like substances, alone or singly, can be detonated easily and faultlessly by the same quantities, when in the combined state in the fuses or ignitors. The explosive ingredients or constituents intimately mixed with the carbon accelerate and intensify to the highest degree the active and effective exchange and combination, of the atoms inside the fuses or igniting contrivances. It is, of a particular advantage that the mixture of the fuse be in an unim-pregnated state, that is to say, without liquid oxygen or other liquefied gas. Explosives mixed with inert substances such as soot, can be handled more freely and with considerably less danger, being less subject and sensible to changes than the charge or contents of the ordinary blasting tubes or fuses consisting only of the explosive mentioned.

The igniting mixture may be saturated, inside or outside the borehole, with liquid oxygen, liquid air, or other liquefied gas. In practical work it is essential that the quantity of the explosive should be equal to that of the ingredients with which it is mixed and which are to be soaked with oxygen. This is particularly important in the case of mixtures that are rather inert.

The carboniferous substance may also be blended with a certain percentage of substances such as, calcium, chlorine, phosphorus, silicon, barium, magnesium, zinc tin, copper, aluminium, iron and their compounds or their salts.

Having thus described my invention, what I claim and desire to secure by Letters Patent is:

1. In a fuse for blasting with a liquefied gas, the combination with substances adapted to absorb liquefied gases, of ready made explosive of high initial power, the said elements being intimately mixed together.
2. In an ignitor for blasting with liquid air, the combination of a carbon carrier adapted to absorb liquid air, and an explosive having a great initial effect, both elements being thoroughly mixed together.
3. In an igniting contrivance for blasting with liquid air, the combination with soot, of azoimide of lead intimately mixed with said soot.

4. The hereinbefore described method of producing fuses for blasting with a liquefied gas, which consists in thoroughly blending a ready made explosive of high initial power with substances adapted to absorb the liquefied gas. 20

5. The method of producing ignitors for blasting with a liquefied gas, which consists in intimately mixing azoimide of lead with soot. 25

In testimony whereof I affixed my signature in presence of two witnesses.

AMBROSE KOWASTCH.

Witnesses:

PETER MEFFERT,
FRITZ SANDHAMP.
